[57] CLAIM

The ornamental design for a bezel for rack mounted device, as shown and described.

DESCRIPTION

FIG. 1 is a perspective view of a first embodiment of a bezel for rack mounted device;

FIG. 2 is a front elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof;

FIG. 8 is a perspective view of a second embodiment of a bezel for rack mounted device;

FIG. 9 is a front elevation view thereof;

FIG. 10 is a top plan view thereof;

FIG. 11 is a bottom plan view thereof;

FIG. 12 is a left side elevation view thereof;

FIG. 13 is a right side elevation view thereof;

FIG. 14 is a rear elevation view thereof;

FIG. 15 is a perspective view of a third embodiment of a bezel for rack mounted device;

FIG. 16 is a front elevation view thereof;

FIG. 17 is a top plan view thereof;

FIG. 18 is a bottom plan view thereof;

FIG. 19 is a left side elevation view thereof;

FIG. 20 is a right side elevation view thereof; and,

FIG. 21 is a rear elevation view thereof.
